Patented Feb. 19, 1963

194,620

PORTABLE ELECTRIC FOOD MIXER

Lionel Grise, Jr., West Brookfield, Mass., assignor, by
mesne assignments, to Electric Spoon, Inc., West Brook-
field, Mass., a corporation of Massachusetts

Filed Jan. 29, 1962, Ser. No. 68,548

Term of patent 14 years

(Cl. D44—1)

The FIGURE is a top perspective view of a portable electric food mixer, showing my new design, the dominant features of which are shown in full lines.

I claim:

The ornamental design for a portable electric food mixer, as shown and described.
